UNITED STATES PATENT OFFICE.

JAMES H. RAND, OF NORTH TONAWANDA, NEW YORK, ASSIGNOR TO RAND KARDEX BUREAU, INC., OF TONAWANDA, NEW YORK, A CORPORATION OF DELAWARE.

INDEX.

Application filed June 18, 1923. Serial No. 645,999.

This invention relates to index devices of the type having holders or panels with index material on both sides thereof.

Objects of the invention are to give an indication upon each side of such holders or panels of the scope of the index material on both sides thereof, to provide an improved form of index strip for tabs, and in general to improve devices of this kind to the end that index items therein may be more readily found.

For the purpose of illustrating the invention one concrete embodiment thereof is shown in the accompanying drawings, in which:—

Fig. 1 is an elevational view;

Fig. 2 is an enlarged detail of a portion of one of the holders or panels shown in Fig. 1;

Fig. 3 is a section on the line 3—3 of Fig. 2 showing the panel in plan; and

Fig. 4 is a plan view of an index strip.

The embodiment of the invention shown for the purpose of illustration comprises a plurality of index holders or panels A arranged detachably to support index strips or cards B upon both sides thereof. In the form shown panels A are mounted for swinging movement upon vertical pivots C in frame D to display the index material upon the opposite sides thereof. Each panel is provided upon its outer free edge with a suitable tab E. This tab may be of any suitable form or construction, one form being shown in elevation in Fig. 2 and in section in Fig. 3. The tab comprises a strip of sheet metal e fast at one end between the sides a of one of the panels, the outer end of metal strip e being bent into parallel relation with the remainder of the strip. This strip e is preferably enclosed or surrounded by a sheath e' of transparent resilient material, such as a celluloid, having a bent end e² enclosing the free edge of strip e and the opposite end e³ wedged between one of the sides a of the panel and the metal strip e, whereby the sheath is securely retained upon the metal strip e. Between sheath e' and strip e are inserted index strips F each having index indicia thereon such as the number of the panel or each side thereof and an indication of the scope or content of the index material not only upon the side upon which the strip is ap-

plied but upon the opposite side of the panel also.

A preferred form of the index strip is shown in Fig. 2 wherein a heavy horizontal line serves to separate the indicia of the content of the two sides of the panel, the indicia above the line referring to the first and last items on the exposed side of the panel and the indicia below the line referring to the first and last indicia on the opposite side. If desired the index strips F to be inserted in the tabs E may be made integral as shown in Fig. 4 in which case the strip is folded lengthwise and then inserted in tab E directly behind the celluloid sheath e' and between it and the metal strip e as shown in Fig. 3.

From the above it will be clear that an improved index strip has been provided for giving an indication on each side of a double faced index panel of the index material content on both sides thereof. This arrangement is particularly useful in an index device of the type such as illustrated shown in Fig. 1, in which a plurality of index panels are mounted for swinging movement to opposite sides to display the index material on the opposite sides thereof. In inspecting such an index device a portion of the panels will ordinarily be disposed with their faces toward the user and the other portion with their backs toward the user. By providing such index panels with index strips of the type shown the user has at all times visible to him a complete index of all the material upon the panels and as soon as he determines from the indication on the several tabs which panel has the item which he desires to inspect the tab of that panel will also tell him upon which side of the panel the item is to be found, since the indicia above the horizontal line refers to the items on the exposed side of the panel and the indicia below the line to the opposite side of the panel.

While but one embodiment of the invention has been shown it is obvious that many changes and variations may be made in adapting the inventive idea herein disclosed to index systems of various kinds without departing from the spirit and scope of the invention.

I claim:

1. In an index device the combination

with a series of holders having index material upon both faces thereof, of indicating means at one edge of each holder showing upon one face thereof the contents of both faces of the holder.

2. In an index device the combination with a series of holders having index material upon both faces thereof, of indicating means adjoining the edge of each face of 10 each holder showing the contents of both faces of the holder.

3. In an index device, a holder having index material upon both faces thereof, means at the edges of said faces displaying 15 identical indicia in reverse order at opposite faces of said holder thereby to indicate at each face of the holder the first item upon that face and the first item upon the opposite face.

20 4. In an index device, a holder having index material upon opposite faces thereof, means at the edge of one face of said holder indicating the first and last items on both faces of said holder.

25 5. In an index device, a holder having index material upon opposite faces thereof, a tab displaying identical indicia adjoining each face of said holder, said indicia indicating the first and last items of each face 30 of said holder and being disposed in reverse order adjoining opposite faces of said holder.

6. An index device comprising a double-faced panel, an index tab extending beyond one edge thereof and arranged to display 35 an index strip adjoining each face of said panel, an index strip on each face of said tab, said strips having identical indicia thereon indicative of the scope of index material upon both faces of said panel.

40 7. An index device comprising a double-faced panel, an index tab extending beyond one edge thereof and arranged to display an index strip adjoining each face of said panel, an index strip on each face of said 45 tab, said strips having identical indicia thereon indicative of the scope of index material upon both faces of said panel, said indicia being in reverse order at opposite faces of said panel whereby the scope of 50 index material on the exposed faces is indicated in advance of that on the opposite face.

8. An index device comprising a double-faced panel, an index tab extending beyond

one edge thereof and arranged to display 55 an index strip adjoining each face of said panel, an index strip on each face of said tab, said strips being integrally connected and having identical indicia thereon indicative of the scope of index material upon both faces of said panel.

9. An index strip for the tab of a double-faced index holder having indicia in duplicate on one face thereof, said indicia being indicative of the scope of the index material 60 on both faces of the holder, said strip being arranged to be folded before insertion in the tab whereby one set of the indicia will appear adjoining each face of the holder.

10. An index element for the tab of a double-faced index holder, said element having indicia in duplicate but in reverse order on adjoining surfaces thereof, said indicia being indicative of the scope of the index material on both faces of the holder, 70 said element comprising a strip of sheet material adapted to be folded before insertion in the tab whereby one set of the indicia will appear adjoining each face of the holder when the strip is so folded with the indicia adjoining each face of the holder referring first to the index material on that face and then to the material on the opposite face of the holder.

11. In an index device, a holder for displaying index material on both faces, a sheath mounted on the edge of the holder, an index element in such sheath, said element having on opposite faces thereof indicia indicative of the index material on opposite faces of the holder respectively, and said sheath being constructed to display said indicia on opposite faces of the holder.

12. In an index device, a holder for displaying index material on both faces, a sheath mounted at the edge of the holder, a folded index strip in said sheath, said strip as folded comprising an element having indicia on both its faces indicative of the index material on the opposite faces of the holder respectively, and said sheath being constructed to display said indicia adjoining each of the faces of the holder.

Signed by me at Boston, Massachusetts, 105
this thirteenth day of June, 1923.

JAMES H. RAND.
